DESIGN FOR A CLOTHESLINE TIGHTENER

Michael Bocchino, Passaic, N. J.

Application May 19, 1937, Serial No. 69,429

Term of patent 14 years

To all whom it may concern:

Be it known that I, Michael Bocchino, a citizen of the United States, residing at Passaic, in the county of Passaic and State of New Jersey, have invented a new, original, and ornamental Design for Clothesline Tighteners, of which the following is a specification, reference being had to the accompanying drawing, forming part thereof and in which:—

The figure is a perspective view of a clothesline tightener showing my new design.

The sides opposite to the sides shown are substantially plain.

I claim:

The ornamental design for a clothesline tightener, as shown and described.

MICHAEL BOCCINO.
